UNITED STATES PATENT OFFICE.

EMIL ZULLIG, OF WEEHAWKEN, NEW JERSEY, ASSIGNOR TO THE AUTOMATIC LACE & EMBROIDERY CO. INC., OF WEEHAWKEN, NEW JERSEY, A CORPORATION OF NEW YORK.

DESIGN FOR FILET-LACE.

51,450.

Specification for Design.

Patented Oct. 30, 1917.

Application filed September 10, 1917. Serial No. 190,686. Term of patent 3½ years.

To all whom it may concern:

Be it known that I, EMIL ZULLIG, a citizen of the Republic of Switzerland, residing at 208 Dodd street, Weehawken, county of Hudson, and State of New Jersey, have invented a new, original, and ornamental Design for Filet-Lace, of which the following is a specification, reference being

had to the accompanying drawing, forming part thereof.

The figure is a plan view of filet lace showing my new design.

I claim:

The ornamental design for filet lace as shown.

EMIL ZULLIG.
